UNITED STATES PATENT OFFICE

97,580

DESIGN FOR A BARREL

Roy C. Ingersoll, Chicago, Ill.

Application September 3, 1935, Serial No. 58,412

Term of patent 14 years

To whom it may concern:

Be it known that I, Roy C. Ingersoll, a citizen of the United States and resident of the city of Chicago, in the county of Cook and State of Illinois, have invented a new, original, and ornamental Design for a Barrel, of which the following is a specification, reference being had to the accompanying drawing, wherein:

Fig. 1 is an end view of a barrel embodying my new design; and

Fig. 2 is a side elevational view of the barrel shown in Fig. 1;

A reference to the drawing will show that the design is embodied in a metal barrel having side walls with end portions wherein there are formed spaced apart axially extending sections simulating barrel staves.

I claim:

The ornamental design for a barrel substantially as shown and described.

In testimony whereof, I affix my signature.

ROY C. INGERSOLL.
